Primary Examiner — Omeed Agilee*(74) Attorney, Agent, or Firm* — Westman, Champlin & Koehler, P.A.; Amanda M. Prose(57) **CLAIM**

The ornamental design for a specimen collector as shown and described.

DESCRIPTION

1. Specimen collector

1.1: Front

1.2: Back

1.3: Left

1.4: Right

1.5: Top

1.6: Bottom

1.7: Perspective

The specimen collector is used to collect and filter a specimen such as feces, sputum, soil, ground thick plant tissue, etc. The broken lines depict portions of the specimen collector that form no part of the claimed design.
